PORATION.

CABINET-DRAWER CONSTRUCTION.

1,143,297.

Specification of Letters Patent. Patented June 15, 1915.

Application filed May 1, 1913. Serial No. 764,877.

To all whom it may concern:

Be it known that we, JESSE C. MOORE, WILLIAM A. MOORE, and FOY WADE, citizens of the United States, and residents of Indianapolis, county of Marion, and State of Indiana, have invented a certain new and useful Cabinet-Drawer Construction; and we do hereby declare that the following is a full, clear, and exact description thereof, 10 reference being had to the accompanying drawings, in which like letters refer to like parts.

The object of this invention is to provide an improved means for mounting drawers or other movable parts in cabinets and the like, wherein the rear portion of the drawer or other movable part is slidably suspended on a rod extending over the drawer or other movable part by a simple means attached to 20 the rear wall of the drawer or other movable part and slidably on the rod and arranged so that said connection is readily adjustable in order to give the rear end of the drawer or other movable part proper 25 relation and centering. While a drawer is herein set forth particularly, the invention may be employed in connection with doors or other movable parts of book cases and other cabinets.

30 The chief feature of the invention consists in adjustably connecting centrally to the rear wall of the drawer, or other movable part, means slidable on a rod for both guiding and supporting the drawer, thus 35 dispensing with all cleats and complex constructions of every kind. One of the chief objects of the invention is simplicity of construction and operation.

Another feature of the invention consists 40 in making a connection between the drawer and guide rod adjustable in the manner above indicated so that the drawer can be drawn out entirely to the front and will not bind with the drawer opening in the 45 front wall of the cabinet, that is, not bind either the bottom or the side walls thereof, and hence the adjustment is such as to enable one to vertically adjust the rear end of the drawer and also to laterally adjust the 50 same to suit the drawer opening in the front wall of the cabinet.

The full nature of the invention will be understood from the accompanying drawings and the following description and 55 claims.

In the drawings, Figure 1 is a vertical longitudinal section through a cabinet having two drawers, showing the drawer closed. Fig. 2 is a perspective view of a portion of the guide rod and the rear of the connecting plate thereon. Fig. 3 is a vertical section through a portion of the rear part of the drawer and the connection between the drawer and the guide rod, parts being broken away. Fig. 4 is a horizontal section 65 through a part of the drawer on the line 4-4 of Fig. 3.

There is shown herein a cabinet 10 having in its front wall drawer openings 11 for drawers 12. The particular construction of 70 these parts is immaterial to this invention.

Centrally over each drawer a guide rod 15 is secured in the cabinet and it should be substantially parallel with the drawer and has a connecting plate 16 secured substantially midway of the rear wall of the drawer and extends upward therefrom and has a hole in its upper end through which the guide rod extends. By this simple connecting plate the drawer is both guided and 75 supported and all cleats and other complex arrangements which interfere with the smooth operation of the drawer, are avoided.

In the form herein shown there is a bearing sleeve 17 in the opening in the upper end of the plate 16 and loosely surrounding the guide rod 15 and with its ends flaring somewhat so that it will slide smoothly and easily on the guide rod and never bind 90 thereon.

The particular construction shown herein to obtain the best adjustment of the connection between the guide rod and the drawer, consists of forming the plate 16 with a wide 95 slot 18 and clamping it to a plate 20 which is secured to the rear wall of the drawer by bolts 21. The clamping is effected by a clamping bolt 22 which screws into the plate 20 and projects through the slot 18 and 100 through a wide washer 23 and said washer is wider than the slot, but the diameter of the bolt 22 is considerably less than the width of the slot. Therefore, the rear end of the drawer can be vertically adjusted 105 with reference to the guide rod 15 and the plate 16 clamped thereto. Also the rear end of the drawer can be laterally adjusted within the range of difference between the diameter of the bolt 22 and the width of the 110

slot and this range of adjustment is sufficient if the plate 20 is properly located in assembling the device. The vertical adjustment arranges the rear part of the drawer so that it will not bind the bottom of the drawer opening 11 when the drawer is drawn out far. The horizontal adjustment enables the rear portion of the drawer to be truly centered so that when it is drawn far out, 10 it will not bind the drawer opening at either side. What is said above relative to a drawer applies also to doors or parts of book cases and cabinets, which parts are bodily movable.

15. The invention is:

1. A cabinet with a drawer opening therein, a drawer, a rod secured in the cabinet substantially midway of the width of the drawer and parallel with its direction of movement, a vertical plate slidable on said rod and having a vertical slot in it, and a clamping bolt extending through said slot and screwed into the rear end of said drawer, said bolt being of less diameter than the width of the slot in said plate, so that said plate can be adjusted laterally and vertically in relation to the rear end of the drawer and be clamped in adjusted position by said bolt.
- 20 2. A cabinet with a drawer opening in one wall thereof, a drawer, a rod secured in the cabinet substantially midway of the width of the drawer and parallel with the drawer and its direction of movement, a plate with a hole through which said rod loosely ex-

tends and said plate having a vertical slot therein, a bolt extending through said slot for clamping said plate to the drawer, the diameter of said bolt being appreciably less than the width of the slot, and a washer on 40 said bolt having a diameter greater than the width of the slot, whereby the drawer can be both vertically and horizontally adjusted.

3. A cabinet with a drawer opening in one wall thereof, a drawer, a rod secured in the cabinet substantially midway of the width of the drawer and parallel with the drawer and its direction of movement, a plate with a hole through which said rod loosely extends and said plate having a vertical slot 50 therein, horizontal corrugations on one side of said plate, another plate secured to the drawer with horizontal corrugations for meshing with the corrugations on said slotted plate, a bolt extending through the slot 55 in said slotted plate and screwing into the plate secured to the drawer and with a diameter less than the width of the slot, and a washer for said bolt with a diameter greater than the width of the slot.

In witness whereof, we have hereunto affixed our signatures in the presence of the witnesses herein named.

JESSE C. MOORE.
WILLIAM A. MOORE.
FOY WADE.
